TRAVEL TIE HANGER OR THE LIKE

James B. Swett, Barrington, R.I., and Sidney Z. Smith, Worcester, Mass., assignors to Dart Industries, Inc., Los Angeles, Calif., a corporation of Delaware

Filed July 16, 1969, Ser. No. 18,219

Term of patent 14 years

Int. Cl. D6—07

U.S. Cl. D80—8

FIG. 2

FIG. 1 is a perspective view of a travel tie hanger or the like embodying our new design; and

FIG. 2 is a cross-sectional view taken along line 2—2 of FIG. 1.

We claim:

The ornamental design for a travel tie hanger or the like, substantially as shown.
